BOOT TREE

Edmund J. Baas, Rochester, N. Y.

Application May 22, 1937, Serial No. 144,267

7 Claims. (Cl. 12—129.3)

The present invention relates generally to what are commonly known as boot trees and is more particularly a device insertable within the leg or top portion of a boot, as distinguished from its foot portion, to preserve its shape between periods of use. The invention may be applied with beneficial effect to riding boots and may be used as well in laced top work boots.

More especially the present improvements 10 contemplate a boot tree which involves a pair of opposed form plates curved transversely to approximately the contour or desired contour of the front and rear of the leg or top portion of a boot within which they are to be positioned, and has 15 for its primary object the positive manually controlled adjustment of the form plates toward and away from each other in an arrangement in which this adjustable pressure is applied through tempering or ameliorating springs functioning 20 to distribute the pressure uniformly throughout the length of the form plates.

A further object may be said to be the arrangement involving manually adjusted pressure applied through means which will at the same time 25 permit the form plates to be shifted toward and away from each other at either end of the tree, independent of such adjustment, as a temporary assistance in the application of the tree within, and its removal from, a boot.

30 A still further object of the invention may be said to be the provision of an arrangement of the above character in which the adjusting means for varying the pressure of the form plates by bodily shifting the latter toward and away from 35 each other, is applied to the plates through springs located in their entirety within the limits of, and between the form plates, so as to be protected and prevented thereby from abrading, cutting or otherwise marring the boots in the use of 40 the tree.

With these general objects in mind, the further and more specific objects of the invention as well as its resulting advantages, will be more readily understood from the following description in detail of the invention, reference being made to the accompanying drawing which forms a part of this specification and in which—

Fig. 1 is a perspective view of the complete boot tree of the present invention.

50 Fig. 2 is a vertical sectional view showing the practical application of the invention.

Fig. 3 is an enlarged fragmentary sectional view illustrating in detail the manner of attaching the connecting and supporting springs to the 55 form plates.

Fig. 4 is a sectional top plan view of the boot tree shown in Fig. 1.

Fig. 5 is an enlarged fragmentary view in section illustrating the proposed connections between the springs and the adjusting stem, and

Fig. 6 is a vertical sectional view through a complete tree, illustrating a slightly modified form.

Referring now to these figures and particularly to Figs. 1 and 2, the two vertically elongated and transversely curved form plates 10 and 11, respectively, the front and rear plates, may be formed of hard fiber board, metal or any other material useful for the purpose, which is capable of being bent to the desired contour and of thereafter retaining such contour. In the present instance, the front form plate 10 is shown to be swelled or flared at its lower portion, as at 12, to extend slightly beneath the instep portion of the boot, such for instance as the boot A of Fig. 2, although it is to be noted this latter shaping may be eliminated since it is contemplated that in any event, in connection with the present invention, it is the top or leg portion of the boot which is to be distended and shaped, irrespective 20 of whether or not a separate shaping device, commonly known as a shoe tree, is employed within the foot portion of the boot. It is not intended that the boot tree of the present invention shall prevent the use of a shoe tree or in any way affect the shoe tree in its functions 25 where it is employed.

Securely fastened at their ends to the central portions of the inner surfaces of the form plates 10 and 11, preferably at approximately the same 30 distances from the upper and lower ends of these plates, are a pair of oppositely disposed U-shaped springs 13 and 14. The connections of these springs with the form plates may, if the latter be formed of fiber or similar material be effected 35 by rivets 15 as shown. If the form plates be however formed of metal, the connections of the springs may be completed by means of end rivets, spot welding, or other suitable instrumentalities.

By thus disposing the springs 13 and 14 in opposing relation and with their ends extending toward the ends of the form plates, the central portions of these springs closely approach each other and through these central portions, the inner end of an adjusting stem 16 is extended, its outer, upwardly projecting end extending beyond the upper ends of the form plates and being provided with a handle 17 by means of which it may be conveniently turned on its longitudinal axis.

In order to effectively associate the adjusting stem with the supporting and connecting springs 13 and 14, its inner threaded end 18 may be extended through a pair of opposing nuts 19 and 20, respectively, connected by suitable means, as by means of spot welding, to the springs 13 and 14. The inner extremity of the adjusting stem 16 may be rotatably mounted as at 21 through the nut 20, as shown in Fig. 5, and in this event the nut 19 will be threaded to cooperate with the threaded inner portion 18 of the stem so that 60

by rotation of the latter the nut 19 will be advanced toward or moved away from the nut 20 depending upon the direction of such rotation. In this way a comparatively slow though fine adjustment is provided for.

On the other hand, as shown in Fig. 6, the adjusting stem 16a may have inner oppositely threaded portions 22 and 23 engaging conformable threads of the nuts 19a and 20a so that upon 10 rotation of the stem both nuts will be moved either toward or away from each other depending upon the direction of rotation of the stem. In this way a more quick adjustment is provided for which may be of some advantage in 15 certain instances of use.

In any event it is obvious that according to the invention the adjustment of the two form plates toward and away from each other and the variation of the pressure of and engagement with 20 the leg or top portion of the boot A will be applied through the spring members 13 and 14 whose relation to each other and to the form plates is such that in tempering or ameliorating the effect of the pressure, they distribute such 25 pressure uniformly throughout the length of the form plates so that the pressure against the boot will be approximately the same at both ends of the tree. It is also obvious that in thus applying the manually adjusting effect of the stem 16 30 through the springs 13 and 14, either end of the tree may be easily rocked to move the respective ends of the form plates toward each other for thus temporarily assisting in the application of the tree within, and its removal from, a boot. 35 By the reverse disposal of the springs not only are their central portions so associated as to permit of ready and convenient application of the adjusting stem, but this arrangement admits of connecting the ends of the springs to the 40 form plates adjacent to the upper and lower ends of the latter without any portion of the springs projecting beyond the form plates so that the latter act to protect the springs and to in turn prevent the springs from any possible abrasion 45 or marring of the boots within which the trees are employed.

What is claimed is:—

1. A boot tree comprising a pair of elongated form plates transversely curved to fit the contour 50 of a boot top or upper, a pair of oppositely disposed curved spring members having their ends extending toward and securely fastened to the end portions of the form plates, with their central portions opposed, and an adjusting screw 55 rod extending lengthwise of and between the form plates, having operative connection through the said central opposed portions of the spring members, including threaded connection with at least one of said spring members whereby upon 60 rotation of the adjusting rod the opposed portions of the springs will be more or less spaced to thus adjust the form plates toward and away from each other.

2. A boot tree including a pair of elongated 65 form plates transversely curved to fit the contour of a boot top or upper, a pair of oppositely disposed curved spring members between said form plates, having their ends extending toward the ends of the form members and securely fastened to the latter at approximately equal points 70 with respect to their ends, said spring members

having apertured central portions in adjacent opposed relation, and an adjusting stem projecting lengthwise of and between the form plates, having a handle at its outer end and a suitable connection at one end through the aperture of 5 one of said spring members, said stem having a threaded portion operatively in connection with the other spring member through its aperture whereby upon rotation of the stem the central portion of the latter spring member will be 10 shifted toward and away from the other spring member to thus adjust the form plates toward and away from each other.

3. A boot tree comprising a pair of form plates transversely curved to fit the contour of a boot 15 top or upper, a pair of oppositely curved spring members having their outer ends projecting toward and securely fastened to the end portions of the form plates and having central apertured 20 portions in adjacent opposed relation, nut blocks 25 secured to the said apertured central portions of the spring members and having threaded bores, and a longitudinal adjusting stem having a handle at its outer end and having at its inner ends oppositely threaded portions in effective engagement 30 through the bores of the nut blocks whereby upon rotation of the stem to shift the central portions of the spring members toward and away from each other to thus adjust the form plates.

4. A boot tree including a pair of opposed transversely curved form plates, a pair of opposed spring members spacing and connecting said plates, and an adjusting member carried by 35 said spring members and operatively associated therewith for adjustably flexing the latter to thus adjust the form plates toward and away from each other.

5. A boot tree including a pair of opposed curved form plates, a pair of oppositely disposed 40 spring members spacing and connecting said form plates and having central opposed portions, and an adjusting means in operative association with said central portions of the springs for adjustably flexing the latter, to thus adjust the 45 form plates toward and away from each other while permitting their free angular manipulation against the tension of the springs.

6. A boot tree including a pair of opposed curved form plates, a pair of reversely curved 50 spring members having their ends projecting toward and secured adjacent to the end portions of the form plates, and an adjusting stem extending longitudinally between the form plates and 55 operatively in connection with the central portions of said springs for flexing the latter to thus adjust the form plates toward and away from each other.

7. A boot tree including a pair of opposed curved form plates, a pair of spring members 60 spacing and connecting said plates, and an adjusting means carried by and operatively associated with said spring members for adjustably flexing the latter to thus adjust the form plates toward and away from each other, said springs 65 and their connection with said form plates permitting either end of either form plate to be rocked to move the ends of the form plates toward and away from each other.

EDMUND J. BAAS.
